UNITED STATES PATENT OFFICE

WILLIAM E. WHITE, OF CHICAGO, ILLINOIS

BAR CLIP

Application filed December 10, 1927. Serial No. 239,078.

My invention relates to concrete reinforcing devices and is a modification of or a variation in the construction disclosed and claimed in my copending application, Serial No. 239,077, filed of even date herewith.

As stated in my said copending application, an object of the bar holding clip disclosed in this and said copending application is to provide a positive bar holding means that shall prevent possible escape of the bar from the clip and yet permit certain limited longitudinal adjustment as required, these advantages to be secured in a construction in which the bar engaging means shall be self acting.

In the construction here disclosed, an additional improvement is provided. Many engineers object seriously to the use of metallic chairs that rest on the forms, for the reason that when the forms are removed, the surfaces of the chairs that originally rested on the forms are then exposed to the weather. The resultant oxidation renders the surface unsightly and offers a possibility of admission of moisture to the reinforcing bars imbedded within the concrete. Consequently in some jurisdictions the use of metal chairs is prohibited, concrete or other non-rusting chairs being required.

An object of the improvement here disclosed is to provide chairs composed of cementitious material and to incorporate bar holding clips therein, the clips being of such construction that the labor of installing the bars is reduced, and the engagement between the bars and the chairs made certain.

I am aware that concrete blocks having a loop of wire therein have been used, the ends of the wire being adapted to be twisted together over the bar. An objection to this construction aside from the increased manual labor required, is that the strain following the twisting of the wires tends to split or break the chair composed of cementitious material, due to the fact that the strain is usually exerted outwardly in two directions.

By a simple expedient adopted for use in this connection, I have avoided this difficulty and eliminate any possibility of breakage of the block due to the strain of engagement

and holding of the bar. The result is accomplished by looping the wire and crossing the wires at their point of emergence from the block. Thus the spreading tendency of the free arms is exerted on a section of material confined within the center of the block and is exerted inwardly instead of outwardly.

The invention will be more readily understood by reference to the accompanying drawing, in which—

Fig. 1 is a sectional view through a pair of concrete blocks and a metallic spacer used for joining the same;

Fig. 2 is a plan view thereof;

Fig. 3 is a transverse sectional view through one of the chairs, and

Fig. 4 is a perspective view of a single chair and clip such as may be employed without the combination with a spacer.

In the construction of Figs. 1 to 3, I have illustrated chairs 10, composed of cementitious material such as concrete, the chairs being joined by a metallic spacer 11 of arcuate form in cross section. This or a similar shape is employed in order to insure rigidity and elimination of distortion in handling. The chairs and spacer are suitably keyed together by means of the anchor 12 or otherwise. The tongue 12 is formed by punching out an opening 13 in the top of the spacer through which the bar clip is inserted.

The clip is in the form of a length of wire bent to provide a loop 14 that is imbedded in the chair. The arms of the loop are crossed at substantially the point of emergence from the cementitious material, and the free ends project diagonally outward and upward and thence diagonally upward and inward, terminating in oppositely and inwardly projecting hooks 14. It will be noted that the outwardly divergent portions 15 of the arms lie snugly against the top surface of the spacer 11, thus constituting another anchor or holding means between the spacer and the block.

When a bar is to be placed in position, it is located directly above the meeting points of the ends and forced downwardly into the position shown at the right hand end of Fig.

1 in which position the hooks overlie the bar and securely hold it against removal vertically; it may, however, be adjusted longitudinally as required.

5 In the construction of Fig. 4 the block 16 is the same and the general construction of the bar clip is the same. The loop 17 is imbedded within the chair, and the arms of the loop are crossed at a point above the chair. 10 The upper portions of the arms are similar to those already described terminating in hooks 18 for the described purpose.

15 It will be noted that in both of the forms illustrated, the force exerted by the bar tending to spread the arms acts merely to compress a body of the cementitious material within the center thereof, there being no tendency to split the chair.

20 Other modifications and changes in the form and arrangement will undoubtedly suggest themselves to those skilled in the art, and do not wish to be limited except as indicated in the appended claims.

I claim:

25 1. In combination, a body of cementitious material and a bar clip composed of wire, a portion of which clip is imbedded in the chair, the two portions of the clip being crossed at substantially their point of emergence from the cementitious material, the free portions of the wire extending upwardly and terminating in oppositely and inwardly projecting hooks.

30 2. In combination, a chair of cementitious material and a bar clip composed of a length of wire doubled on itself to form a loop, the loop being imbedded in the chair, the arms of the loop being crossed at substantially the point of emergence from the material composing the chair, the free ends of the wire projecting upwardly and terminating in oppositely and inwardly projecting hooks.

35 In testimony whereof I have affixed my signature.

WILLIAM E. WHITE.
